GAS EXPANSION AND ABSORPTION PROCESS AND APPARATUS THEREFOR

Original Filed Oct. 21, 1920

UNITED STATES PATENT OFFICE.

JOHN C. BERTSCH, OF TULSA, OKLAHOMA.

GAS EXPANSION AND ABSORPTION PROCESS AND APPARATUS THEREFOR.

Application filed October 21, 1920, Serial No. 418,569. Renewed September 9, 1922. Serial No. 587,231.

To all whom it may concern:

Be it known that I, JOHN C. BERTSCH, a citizen of the United States, residing at Tulsa, in the county of Tulsa and State of Oklahoma, have made a new and useful Invention in Gas Expansion and Absorption Process and Apparatus Therefor, of which the following is a specification.

This invention relates to improvements 10 in the recovery of vapor from a gas by absorption, and forms an extension of the invention covered by my co-pending application for U. S. Letters Patent, Serial No. 415,336.

An object of the invention is the churning of a liquid in the presence of a gas during the compression of the latter.

Another object of the invention is the alternate mixing and separation of a gas and a liquid in stages for subjecting gas and liquid of approximately the same vapor content repeatedly to each other.

Another object of the invention is the circulation of the absorbent liquid during its distillation and cooling by its own energy without mechanical aid.

Still another object of the invention is the rectification of the recovered fluid and commercial utilization of the resulting by-product.

A further object of the invention is to provide relatively cheap and semi-portable means for the extraction of vapor from a gas containing it.

35 With these and other objects in view, as will more fully appear hereinafter, the invention consists of certain novel features of procedure and arrangements of parts, hereinafter fully described, illustrated in the 40 accompanying drawing and pointed out in the appended claims.

In the absorption methods practiced at present, from 4 to 6 gallons of absorbent are circulated per 1000 cubic feet of gas and 45 saturated with the vapor of the gas to from 3 to 5 per cent, so that the yield is seldom more than one half of the total vapor content of the gas. This inefficiency is caused by the poor mixing and relatively short time of contact between gas and liquid, and requires relatively great quantities of heat and cooling water for distillation, besides causing a great waste of valuable fluid.

50 Furthermore, an absorption installation of present construction requires a number of pumps and auxiliary machinery with ex-

pensive foundations and buildings, which render impossible the use of units of a relatively small capacity and the removal of a plant to other locations in case the gas supply fails. Present day plants require also a relatively large operating force, which, together with the unrecoverable loss of unstable fluid produced, results in a relatively high cost of production. 60

65 These defects are eliminated by my present invention, in which yields of up to 95 per cent of the total vapor content of a gas, and a saturation of from 8 to 15 per cent with a circulation of from 10 to 20 gallons 70 of liquid per 1000 cubic feet of gas are obtained with substantially no loss of gas or liquid, thus reducing the consumption of fuel and cooling water for distillation greatly.

According to my invention, the only moving part is a gas and liquid handling rotary pump, which like the expander-absorbers and parts of the distilling apparatus are self-contained and require no expensive foundations and housings, so that a complete apparatus can be cheaply constructed in units of small capacity and semi-portable for a quick removal and re-installation at other locations. 75

80 Owing to the automatic operation of the expander-absorbers and the gravity circulation of liquid and heating agent during distillation, the operation of an apparatus according to my invention is substantially automatic and requires but little attention, 85 which makes it particularly adapted for rural districts and isolated places.

Throughout the further description of my invention the terms "gas", "vapor" and "liquid" are applied in the same sense as 90 in said co-pending application Serial No. 415,336, that is for any gas and liquid of whatever composition and from whatever source, respectively, whereas the term "fluid" refers only to said liquefied vapor. 95

100 In the drawing: a rotary pump 10 receives gas or vapor from a source —S— through suction conduit 11 into which a liquid is injected through pipe 14, and puts the mixture of gas and liquid under the pressure required for doing all the mechanical work during the process. By this operation the liquid is heavily agitated at increasing pressure in the presence of the gas and vapor which are washed and intimately mixed 105 with the liquid; and owing to the great difference in specific heat,—that of the liq-

uid being approximately 5 times greater than that of the gas,—and the greater weight of the liquid,—which is from 30 to 300 per cent greater than that of the gas,—the compression of the gas occurs in a substantially isothermal cycle.

The mixture under pressure is discharged through conduit 12 into a separator 13 in which the bulk of liquid is separated to be used as will be stated later, the gas and entrained portion of liquid leaving through pipe 9. If the nature of the gas and the pressure carried require cooling, or a suitable refrigerant is available for beneficially reducing the temperature of the gas before entering the expander-absorber, the compressed gas may be passed through a cooler —G—. The liquid under pressure leaves separator 13 through pipe 20 to be fed into expander —C— either directly or indirectly by using first its pressure energy in an injector or pump 21 for feeding with it a quantity of fresh liquid from receiver —R— or from cooler —L— through pipe 22. The principles involved in, and work done by the expander-absorbers —A—, —B— and —C— are fully described in my co-pending application Serial No. 415,336, so that it may suffice to describe here only the passage of gas and liquid through three of them, while in practice their number may be more or less, depending upon the pressure of the gas and effect desired.

The gas passes in succession through pipe 15, expander —A—, pipe 16, expander —B—, pipe 17, expander —C— and pipe 18, in the direction indicated by arrows, and then through a separator 33 for depositing any entrained liquid, leaving as residue gas through pipe 34 to be suitably disposed of.

The liquid entering through pipe 22 passes in opposite direction to the gas, first through expander —C—, then through pipe 23, expander —B—, pipe 25 and expander —A—, during which it is mixed with the gas, elevated and cooled by the expansion of the latter, and separated again from the expanded gas in each of the expander-absorbers, leaving in a saturated condition through pipe 19, the liquid deposited in separator 33 gravitating into pipe 22.

For starting the apparatus with gas of normal pressure, the head of the liquid is reduced by withdrawing liquid from either one or all expanders through pipes 36 and manifold 37, placing it temporarily into receiver —R— which is also the storage for fresh liquid, to be gradually returned into the expanders through pipe 22 by device 21.

The process so far described answers fully for all cases in which a distillation for the recovery of the absorbent liquid is not desired. Examples of such cases are: the expansion of a gas for the sole purpose of cooling, as in gasoline extraction plants for utilizing

high pressure denuded gas for reducing its pressure; or the expansion of mixtures of air and gas or vapor for the recovery of the latter by saturating a liquid with it, as in rubber factories, oil refineries and gasoline blending plants; or the expansion of ammonia gas for saturating with it water or weak ammonia liquor; or other similar processes in which the cooling and saturation of a liquid with the vapor content of a gas is contemplated.

However, the elevation of the liquid and putting it under pressure by the expansion of the gas is also an important feature in all other cases in which distillation is required, because the pressure energy imparted to the liquid is utilized during its further disposition with the exclusion of mechanical aid, as will more fully appear hereinafter.

When the gas exists under a suitable pressure, as for example the natural gas issuing from oil and gas wells; or that available in refrigerating and gasoline plants operating on the compression system; or that produced in refineries and cracking plants working with pressure stills, pump 10 and separator 13 are dispensed with, and the gas from source —S— enters expander —A— directly through pipe 15, being also used for operating feeding device 21 by means of pipe 8 shown by dotted line.

In all cases of vapor recovery with the repeated use of the absorbent liquid, distillation is necessary, and the apparatus commonly employed consists of a heater —F—, a still 40, heat exchangers 39 and 41, a liquid cooler —L—, a vapor condenser —V—, and a separator 42 with safety valve 43, all suitably interconnected by conduits and provided with valves and regulating devices, not shown on drawing.

As practiced heretofore, the liquid must be pumped from one device to the other, whereas according to my invention it passes through the whole apparatus in a continuous cycle, and all the resistances of the system are overcome by the elevation and pressure imparted to the liquid by the expansion of the gas, thus eliminating all pumps and intermediate receiving vessels, and greatly reducing the operating expenses.

The elevated and saturated liquid leaving expander —A— under pressure through pipe 19 passes in succession through heat exchanger 39, pipe 45, coil 46, pipe 47, and atomizer 48, for being pre-heated prior to its entry into still 40, first by the still vapor in heat exchanger 39, and then again by the liquid from still 40 in heat exchanger 41. Within still 40, the vapor contained in the preheated liquid is vaporized by means of a heat carrier circulating in a closed circuit through a heater —F—, riser 54, coils 49 and return pipe 55, the fuel supply to heater —F— being indicated by a pipe 56. The

heat carrier may be either steam, water or oil, circulating on the gravity system and being maintained at any desired temperature by a thermostatically regulated fuel supply

5 to heater —F—. In like manner, the saturated and hot liquid as well as condensate, are circulated by their own pressure or heads respectively, which is due to the location of the different parts with relation to the ex-

10 pander-absorbers and to each other.

The flow of the saturated liquid to still 40 is caused by the pressure upon it on top of expander —A—, whereas the flow of the hot liquid through heat exchangers and 15 cooler, and that of the condensate from condenser —V— is due to gravity. The pressure upon the saturated liquid in expander —A— is just a few pounds less than the initial gas pressure minus the pressure 20 in the still 40, which is but slightly above that in separator 33 for allowing safety valve 43 to discharge into pipe 60.

The head required for passing the liquid from still 40 through heat exchanger and 25 cooler into supply pipe 14 and 53, is obtained by placing still 40 sufficiently high above pump 10, which height is only limited by the level of the top of expander tube 27. This arrangement eliminates all pumps as 30 well as constant and close attendance, thus assuring a substantially automatic operation at a greatly reduced cost of production.

The vapor generated in still 40 passes through pipe 57, coil 44 and pipe 58 into 35 condenser —V—, giving up a part of its heat to the saturated liquid flowing through heat exchanger 39.

The hot liquid leaves still 40 substantially free of vapor through pipe 50 and passes 40 through heat exchanger 41, pipe 51 and cooler —L— to be cooled therein by the action of cooling water after giving up a part of its heat to the saturated liquid flowing in coil 46. The so cooled liquid may 45 be further cooled by refrigeration, as will appear hereinafter, or be passed through pipe 52 into pipes 53 and 14 for feeding expander —C— and pump 10, respectively, in the manner described above.

50 According to its character, more or less gas is dissolved in the liquid during the absorption period, producing an unstable fluid and causing a considerable loss of gas and vapor by re-evaporation upon exposure to the 55 atmosphere, which is called "weathering."

To overcome this defect, and to produce a stable fluid without weathering, and consequently without loss of gas or vapor, and at the same time utilizing the refrigerating 60 effect of the vaporized portion of the condensate for lowering the temperature of the absorbent liquid leaving cooler —L—, a rectifier 61 containing a coil 62 and having a relief valve 63 and fluid outlet 64, is connected with conduit 59, the inlet of coil 62

being in communication with liquid cooler —L— by pipe 65 and its outlet with pipe 52 by a conduit 66.

The fluid enters rectifier 61 through pipe 59 and is sprayed over coil 62 by an atomizer 70 67; the liquid from cooler —L—, instead of passing directly into pipe 52, is by-passed into coil 62 through pipe 65, and being of a relatively higher temperature than the fluid sprayed over coil 62, causes the evaporation 75 of the lightest and undesirable portion, consisting chiefly of dissolved gas, whereby its temperature is lowered. The so cooled liquid enters pipe 52 through conduit 66, and the rectified fluid is withdrawn through pipe 64, whereas the vaporous portion leaves rectifier 61 through relief valve 63 to be disposed of through pipe 68 as a by-product, either as fuel, or as a high tension fluid by re-compression and liquefaction under a 80 suitable pressure. The non-condensable portion of vapor in condenser —V— is collected in separator 42 and escapes through safety valve 43 into pipe 60 through which it passes into separator 33 to be mixed with the residue gas from expander —C—.

According to the extent of heating desired within rectifier 61, the temperature of the liquid leaving cooler —L— may be regulated by the amount of cooling water used; or instead of the liquid from cooler —L—, either the gas from separator 13, or the vapor or liquid from heat exchanger 39, or the liquid to or from the heat exchanger 41 may be bypassed through coil 62 in like manner and 100 with a correspondingly greater or lesser heating effect as that described above.

Having thus fully described my invention, it must be understood that the drawing is only a diagrammatical view of an apparatus adapted for carrying out my invention, for which I include as applicable any gas, vapor or liquid of whatever composition or from whatever source, wherefore it is obvious that on account of the greatly 105 varying character and composition of the gas vapor and liquid employed in the process, the same procedure and apparatus cannot be followed in every detail as described and illustrated, so that numerous changes, 110 modifications, additions and omissions may be required for carrying out my invention, without in the least affecting the principles involved.

And because of the intimate nature of 120 process and apparatus, in so far as they are not claimed in my co-pending application for United States Letters Patent, Serial No. 415,336, I wish to claim both process and apparatus in the one application, and in the 125 claims I desire to include any part, not only as named, but as its equivalent.

What I claim as new and desire to secure by Letters Patent is:

1. The absorption process which consists 130

- in mixing a gas and a liquid and putting the mixture under pressure; expanding the gas of said mixture in the act of elevating its liquid and saturating it with the vapor contained in the gas; mechanically separating the expanded gas from the saturated liquid and from the latter the vapor by heat; liquefying said vapor and cooling the denuded liquid, and mixing the latter again with gas.
2. The absorption process which consists in mixing a liquid with a gas under pressure; expanding the gas of the mixture so formed in the act of elevating the liquid and saturating it with the vapor of the gas; separating the expanded gas from the saturated liquid and from the latter the vapor by heat; liquefying said vapor and rectifying the resultant fluid; and cooling the denuded liquid and mixing it again with gas.
3. The absorption process which consists in mixing a gaseous fluid with an absorbent liquid and churning the latter while compressing the former; expanding the compressed fluid in the act of elevating said liquid and saturating the latter with the expanding fluid; and separating the unab-sorbed expanded fluid from the saturated liquid.
4. The process of recovering vapor from a gas containing it, which consists in mixing said gas with a liquid and churning the latter while putting the mixture under pressure; alternately separating said mixture and transferring the resultants to multi-stages and mixing them therein at different pressures; expanding the gas of the mixture in each stage in the act of elevating its liquid and saturating the same with the vapor of the gas; separating and withdrawing the saturated liquid from the highest pressure stage and dissociating it by heat; separating and withdrawing the denuded gas from the lowest pressure stage for commercial utilization; condensing said dissociated vapor and rectifying the resultant fluid; and cooling said dissociated liquid and mixing it with gas.
5. In a process of absorbing the vapor content of a gas under pressure, the steps of mixing a liquid with said gas and expanding the latter in the act of elevating said liquid and saturating the same with the vapor of said gas.
6. In a process of absorbing vapor from a gas containing it, the steps of mixing the gas with a liquid and churning the mixture so formed; then putting said mixture under pressure and expanding its gas in the act of elevating its liquid; and saturating said liquid with the vapor of said gas during said expansion of the latter and separating the expanded gas from the saturated liquid.
7. The process of absorbing the vapor content of a gas in multi-stages, which consists in mixing the gas with a liquid and agitating the same while putting the mixture under pressure; separating said mixture and feeding the first or highest pressure stage with the compressed gas and the last or lowest pressure stage with liquid by said liquid under pressure; transferring said gas and liquid under pressure from stage to stage in opposite direction to each other while mixing in each stage the entering gas and liquid; expanding in each stage the gas of the mixture in the act of elevating its liquid and separating the partially expanded gas from the elevated liquid under pressure; withdrawing from the last stage the denuded gas and from the first stage the saturated liquid under pressure; dissociating the latter by heat and liquefying the vapor so obtained while cooling the denuded liquid; and circulating the latter by gravity and said saturated liquid by its pressure energy.
8. In a process of recovering a fluid from a saturated liquid under pressure, the steps of circulating said liquid without mechanical aid by its own pressure energy and dissociating the same by heat; condensing the dissociated vapor and rectifying the resultant fluid; circulating the dissociated liquid by gravity and cooling it; and saturating the cooled liquid while putting it under pressure.
9. An absorption apparatus comprising a plurality of vertical vessels connected with each other in series, each being arranged for receiving at the bottom and discharging on top a gas and a liquid and for transferring the same from vessel to vessel in opposite direction to each other; a rotary compressor adapted for churning said liquid mixed with said gas during the compression of the latter and communicating with a separator receiving said mixture under pressure, said separator having outlets for gas and liquid communicating with the first and last of said vessels, respectively; a feeding device in communication with said separator a source of said liquid and the last of said vessels; heat exchangers and a still serially connected and communicating with the liquid discharge of the first of said vessels and receiving saturated liquid therefrom; a heater communicating with said still in closed circuit and adapted for gravity circulation of a heat carrier through the same; means for condensing the vapor from said still and for rectifying the resultant fluid; and means for cooling and delivering the denuded liquid from said still to said compressor and feeding device.
10. In an absorption apparatus in combination with vertical absorbers and sources of gas and liquid, a rotary compressor adapted for compressing a gas mixed with a liquid and churning the latter during the compression of the former, having its inlet communicating with the sources of gas and

liquid and its outlet with a separator into which the churned mixture under pressure is discharged, said separator having outlets for gas and liquid under pressure; a feeding device communicating with the liquid outlet of said separator the source of liquid and said absorbers and adapted for feeding the latter with said liquid; and a conduit making communication between the absorbers and gas outlet of said separator.

11. In an absorption apparatus in combination with a vapor condenser fluid receiver heat exchangers and liquid coolers, a fluid rectifier in communication with said condenser and receiver, having means for heating the fluid and vaporizing its unstable portion and provided with means for separating and discharging the rectified fluid and unstable vapor, said heating means communicating with said heat exchangers and liquid coolers for utilizing the respective liquids circulating through them as heating agents; and means for converting said unstable vapor into commercial by-products of the process.

12. An absorption apparatus comprising a rotary compressor adapted for mixing a gas with a liquid and churning the latter during the compression of the gas, having an inlet communicating with sources of gas and liquid and an outlet with a separator receiving said mixture under pressure and having outlets for gas and liquid; a feeding device communicating with the liquid outlet of said separator and source of liquid; a series of vertical vessels each having bottom

inlets and top outlets for gas and liquid, said gas inlets and outlets and liquid inlets and outlets communicating with each other, respectively, in opposite directions to each other except the gas inlet and liquid outlet of the first of said vessels and the liquid inlet and gas outlet of the last of said vessels; conduits connecting the gas outlet of said separator with the gas inlet of the first of said vessels and the liquid inlet of the last of said vessels with said feeding device; heat exchangers and an elevated still serially connected and in communication with the liquid outlet of the first of said vessels and adapted for gravity circulation of the denuded liquid, said still having means for circulating a heat carrier; a heater communicating with the heating means of said still and arranged for circulating the heat carrier in closed circuit; a vapor condenser in communication with said still and receiving vapor therefrom; a fluid rectifier communicating with said condenser and a source of heat and arranged for circulating a heat carrier in closed circuit through the same and for withdrawing the rectified fluid and automatically expelling the unstable vapor; means for cooling said denuded liquid and supplying it to said compressor and feeding device, and means for abstracting heat from the contents of said condenser and cooling means by a cooling agent.

In testimony whereof, I have hereunto subscribed my name this 18th day of October, A. D. 1920.

JOHN C. BERTSCH.
